ELECTRICALLY OPERATED VACUUM
CLEANER

Rubin Bass, Brooklyn, N. Y., assignor to American Plush & Velvet Pressboard Co., Inc., New York, N. Y., a corporation of New York

Application August 5, 1932, Serial No. 627,640

8 Claims. (Cl. 15—7)

My invention relates to apparatus sometimes called vacuum cleaners and especially a rotary brush type.

Among the objects of the invention are to provide a simple, inexpensive, compact, reliable, durable and well balanced device of small size which can be readily manufactured, inspected, cleaned and repaired.

Special objects are to provide a casing which is smooth on the outside so that it will not catch on fabrics being cleaned, to prevent overheating, to avoid so far as possible clogging of the brush or damage to the belt and to facilitate removal and replacement of the brush and cleaning of the brush and belt chamber. The drawing illustrates the preferred form of the invention.

Fig. 1 is a vertical longitudinal sectional view illustrating the invention.

Fig. 2 is a horizontal sectional view substantially on the plane of the line 2—2 of Figure 1, with a part of the flange of the hood member broken away.

Fig. 3 is a vertical transverse sectional view showing the brush and its supports.

Fig. 4 is an inside view of a fragment of the bottom plate.

Fig. 5 is a transverse sectional view of the brush.

Fig. 6 is a longitudinal sectional view showing parts of a brush and its bearing.

Fig. 7 is a fragmentary section showing the support for the motor field at right angles to Figure 1 on line 7—7.

The casing is made up of two parts, the lower or body member casting 10 containing the brush and suction device and the upper one-piece hood member 11 containing the motor with its brushes and switch and a cooling fan. These two parts have appropriate chambers separated by a partition or intermediate plate 12 and are held together by a number of screws 14.

The motor is preferably of the universal type having a rotating armature 15 with a shaft 16, a top bearing 17 in the upper end of the hood and a bottom bearing 18 in the plate 12. As particularly shown in Figure 7, the field structure 19 including field coils 19'' is suitably secured to a sleeve 20 by screws 19' which engage in lugs 20' which are bent inwardly from the wall of the sleeve 20, this sleeve has a flange clamped between the base flange of the hood 11 and the bottom plate 12 by screws 14'. This sleeve 20 also has inwardly pressed strap portions 21 which support suitable brush structures 22. The hood is provided with an opening 23 which per-

mits ventilation and also makes it possible to inspect the commutator and brushes without taking the case apart. Certain parts of the field structure are cut away as shown in Figure 1 to decrease the weight of the structure and to provide for a better air passage within the sleeve 20. The circuit is controlled by a suitable switch 24 which is secured to the sleeve 20 and provided with an external operating knob in the usual manner.

In order to prevent the motor from overheating I preferably provide a fan 25 which is secured to the upper part of shaft 16 and the hood 11 is provided with a number of openings 26 to permit the circulation of air around the upper part of the motor and upper bearing. The fan 10 and armature are assembled and inserted into the hood as a unit and then the sleeve with the field structure and brushes. By mounting the brushes and switch in the sleeve near the mouth of the hood I am able to make the hood perfectly smooth on the exterior. 15

The suction fan or blower 30 is mounted on the lower end of the shaft 16 beneath the plate 12 and in the suction chamber 31 being held in place by the pulley 32 which is screwed on to 20 the bottom of the shaft. 25

The bottom of the body of the casing is provided with a chamber 33 which contains the driving pulley 32 and the brush 34 and the quarter turn belt 35 which connects the pulley 32 and the pulley 36 of the brush structure. The brush is so constructed that it can be inserted and removed as a unit to facilitate cleaning and replacement. The belt 35 is preferably formed of elastic rubber. The shaft 37 or spindle of the brush is preferably tubular and provided with anti-friction bearings 38 supported in metal housings 39. These bearings and housings are removably mounted on the ends of the shaft 37 and held in place by the eyelet members 40 which fit snugly 30 in the ends of the shaft. Each end of the brush shaft is preferably provided with a guard washer 41, the flange of which extends outwardly over the rim of the housing 39 so as to prevent threads and dust and lint from getting into the bearings. The brush is also preferably provided with fins 42 or plates arranged between the brush tufts so that when threads are wound up on the brush they will be spaced apart from the shaft in such a way that it will be easy to insert the point of a pair of shears for the purpose of cutting the threads and removing the same. 45

These fins may be suitably formed, for instance, by stamping them into channel-like shape and riveting or otherwise securing them to the shaft 50 55

37. Preferably these fins are concave along their edges and of less radial extent in the center of each brush section than at the ends of the brush sections. The result is that the threads tending to collect on the shaft are naturally drawn toward the center where they can be more easily cut and removed.

10 The opposite sides of the chamber 33 are provided with open ended bearing sockets, 43, into which the hubs of the housings 39 are adapted to be inserted and secured. Spring abutments 44 are preferably provided to engage the hubs of the brush bearings.

15 It will be noted that the entire bottom of the casing chamber 33 is open so as to facilitate inspection of the brush and belt and removal for cleaning and replacement. A bottom plate 45 is hinged to the casing at 46 and provided with a flange 47 which fits within the edge of the chamber 33. The relatively narrow part of this bottom plate 45 is off-set from the remainder so as to provide a foot provided with two openings or mouths 48—48 separated by a bridge 49 which covers the belt. This bridge is preferably provided with flanges 50 which overlap the edges of the pulley 36 so as to protect the belt and the pulley from thread, dirt, etc.

20 Flanges 51 are also preferably provided to guard the edges of the bearing flanges or washers 41 and prevent thread and dirt from clogging up the ends of the brush. The bottom plate 45 has lugs or abutments 52 on opposite sides adapted to press against the hubs of the bearing members 39 to hold them in place against the yielding pressure of the springs 44.

25 The upper part or hood of the casing and the body of the casing may be formed of aluminum or other light metal or alloy, to keep down the weight and improve the appearance of the device. A yielding steel or other durable latch 53 is secured to the bottom plate inside the casing where it engages the spring pressed plunger 54 to yieldingly hold the bottom plate in place against the pressure of the springs 44. The bottom plate 45 is extended to form a finger-piece 55 to facilitate opening the casing for inspection, repair, etc.

30 The bottom plate is so constructed so as to prevent any part of the brush structure (except the bristles) from coming in contact with the fabric being cleaned.

35 It is understood that the device may have a handle portion 56 with an extension 57 of any suitable sort and provided with a suitable dust collecting receptacle as usual if desired. The apparatus can also be used for blowing purposes and for fumigating or deodorizing without a dust-bag, in which event the brush may also be removed or a fumigator may be employed together with the dust removing brush and collecting bag.

40 The construction of the brush with the attached bearings and guard members is claimed in my application 646,603, filed December 10, 1932.

I claim:

45 1. A vacuum cleaner device comprising a casing having a suction and brush chamber open at the bottom, sockets at opposite sides of the brush chamber open downwardly of the chamber, a resilient bumper in the upper part of each socket, a brush having a shaft with anti-friction bearings secured on the ends thereof and detachably mounted in said sockets, a bottom plate hinged to the casing adjacent the brush and having an opening beneath the brush through which only the bristles of the brush can protrude, said plate 50 having abutments holding the bearings in place

and a latch for the bottom plate capable of holding it in place against the pressure of the resilient bumpers, said plate having a finger piece to facilitate release of the latch and opening of the plate.

5 2. A vacuum cleaner having a casing with a removable cover plate, said casing having open sockets in its side walls, a brush having a shaft with anti-friction bearings mounted in said sockets, the sockets being open to permit the ready insertion and removal of the brush shaft and its 10 bearings said cover plate having abutment lugs coacting with said bearings to hold the brush in place, a resilient bumper in each socket pressing the bearings on the ends of the shaft against said lugs and means for holding the cover plate 15 in place.

3. A vacuum cleaner having a casing with a brush chamber, a brush mounted to rotate in the casing, a detachable bottom plate for the chamber having an opening for operation of the brush, 20 bearings for the brush detachably mounted in the casing and having guard washers, and flanges on the plate overlapping the edges of the guard washers to prevent threads from interfering with the 25 bearings.

4. A vacuum cleaner having a casing, a brush having a shaft and drive pulley with bearings detachably mounted in the casing, and a cover plate having guard flanges overlapping an edge of the pulley and the bearings to prevent threads from 30 interfering with the pulley and its belt and the bearings.

5. A vacuum cleaner device having a casing with 35 sockets, a brush having bearings detachably supported in said sockets, a bottom plate for the casing having an opening for the action of the brush, said brush having guard washers adjacent the bearings and the plate having guard flanges overlapping the rims of the washers.

6. In a vacuum cleaner, a brush having a spindle 40 with a pulley for a driving belt, bristles fastened to the spindle, a housing for the spindle having openings for the bristles to pass therethrough and flanged guard plates formed on the housing and 45 overlapping the edges of the pulley in a manner to protect the belt from thread, dirt, and the like.

7. A vacuum cleaner device comprising a body portion containing a brush and suction device, a motor for driving said brush and suction device, comprising a stator, a rotor, a shaft for said rotor, 50 bearings for said shaft, and motor brushes, a partition between said body portion and said motor, one of said bearings being located in said partition, said shaft extending through said partition 55 and driving said brush and suction device, a sleeve mounted on said body portion, said stator and said motor brushes secured within and supported by said sleeve, a hood surrounding and completely enclosing said sleeve, a second bearing 60 being secured within said hood, and being removable therewith, and means for securing said hood directly to said body portion.

8. A vacuum cleaning device comprising a body 65 portion containing a brush and a suction device, a motor for driving said brush and said suction device, a partition between said motor and said body portion, said motor comprising a stator, a rotor, a shaft for said rotor and bearings for 70 said rotor shaft, one of said bearings being located in said partition, said shaft extending through said partition and driving said brush and said suction device, a sleeve mounted on said body portion, said stator and said motor brushes being 75

secured within and supported by said sleeve, a hood surrounding and completely enclosing said sleeve, a second bearing being within said hood and being removable therewith, said first bearing having a bearing surface substantially longer than said second bearing, a commutator on said rotor,

said motor brushes coacting with said commutator, said commutator and said motor brushes being located adjacent said first bearing and said partition at one side of said partition and said suction device being located adjacent its other side.
